UNITED STATES PATENT OFFICE.

MAX SONNENFELD, OF NEW YORK, N. Y.

NEEDLE-THREADING DEVICE.

1,070,927.

Specification of Letters Patent. Patented Aug. 19, 1913.

Application filed November 28, 1910. Serial No. 594,478.

To all whom it may concern:

Be it known that I, MAX SONNENFELD, a citizen of the United States, and resident of New York, in the county of New York and State of New York, have invented certain new and useful Improvements in Needle- Threading Devices, of which the following is a specification.

This invention relates to devices for threading needles and has in view simplicity of construction and ease of use, as will now be described, reference being had to the following specification and claim and the drawing on which—

15 Figure 1 is an elevation of the device; Fig. 2 is an elevation of the device with a thread hanging in the slot, ready to be passed through the eye of a needle; Fig. 3 shows the device with a thread attached and passed through the eye of a needle; Fig. 4 shows the thread inserted in the eye of a needle with the device detached.

20 In the drawing, there is shown a bar A, preferably of steel and small enough to be pushed through the eye of a needle, with room for the thread to be inserted. The bar A has one end rounded or pointed, and the other end is attached to a handle D.

25 Near the pointed end B, is an oblique slot or incision C inclined toward the end or point B.

30 When the device is used, a thread E is first inserted in the slot C. This can readily be done by sliding the thread along the bar A. The thread is allowed to hang freely, as shown, while the bar A with the dependent thread is pushed through the eye H of a needle G, as shown in Fig. 3. On 35 withdrawing the bar A, the thread E is released from the slot or incision C and is held in place by friction in the form of a

loop F. From this loop, one portion of the thread is pulled through the eye and the 45 threading is completed. If it is desired to use two strands of thread, the looped portion is pulled out to the desired distance, and the needle is threaded with a double 50 thread.

The threading device may be used in all sizes for all kinds of needles from the finest sewing needle to the biggest drawing needle or other still larger needles. It has the advantage that in use one hand is left free 55 to hold the needle, while being threaded, and the other is left free to hold the device, the thread during the operation being securely held in place by gravity.

50 So easy is it to thread a needle by means of this device that it can be readily done by a blind person. When the device is designed for needles of large size, the handle D may be dispensed with.

I am aware of a number of devices for 60 threading needles, some of which bear some resemblance to this. None of these devices is here referred to specifically, because the difference between them and applicant's device is clearly set forth in the terms of 65 70 the claim.

What I claim as new is:

A device for threading needles consisting of a bar provided with an oblique incision near one of its ends, with the opening to- 75 ward that end.

Signed at New York in the county of New York and State of N. Y. this 23d day of Nov. A. D. 1910.

MAX. SONNENFELD.
